UNITED STATES PATENT OFFICE

GUY L. ALLEN, OF DALLAS, TEXAS

ELEVATOR-DOOR-OPERATING APPARATUS

Application filed May 12, 1928. Serial No. 277,181.

This invention relates to new and useful improvements in elevator door operating apparatuses.

One object of the invention is to provide an improved door operating means normally free from contact with the moving car, whereby wear and objectionable noises are eliminated as the car passes the floor landing when the door is closed.

Another object of the invention is to provide a door operating means which is locked when the door is closed, whereby the door is held against opening until the device is positively operated by the operator of the car.

A still further object of the invention is to provide an elevator door operating apparatus including a tripping device arranged to be manually operated with only a slight physical exertion for causing the door opening means to be released and set to operate to open the door.

Another object of the invention is to provide a vertical movable prime mover and a clamping device connected with the door operating means arranged to clamp said mover, whereby motion is transmitted to the door operating means to close the door.

A particular object of the invention is to provide a door operator arranged to automatically open the door, when released, whereby no power or labor is required to open the door.

A still further object of the invention is to provide a prime mover clamping device and a lock, both actuated by a common operator.

A construction designed to carry out the invention will be hereinafter described, together with other features of the invention.

The invention will be more readily understood from a reading of the following specification and by reference to the accompanying drawings, in which an example of the invention is shown and wherein:

Fig. 1 is a view partly in section and partly in elevation showing an elevator door operating mechanism constructed in accordance with the invention, the doors being closed.

Fig. 2 is a similar view showing the doors open.

Fig. 3 is a horizontal cross-sectional view taken on the line 3—3 of Fig. 1.

Fig. 4 is a vertical sectional view taken on the line 4—4 of Fig. 1.

Fig. 5 is an enlarged sectional view of the clamp and locking device.

Fig. 6 is a horizontal cross-sectional view taken on the line 6—6 of Fig. 5.

Fig. 7 is a vertical sectional view taken on the line 7—7 of Fig. 5.

Fig. 8 is an enlarged cross-sectional view taken on the line 8—8 of Fig. 4, and

Fig. 9 is a detail of the tripping cam.

In the drawings the numeral 10 designates an upright support which may be a channel as is shown, or any other suitable and available supporting structure. Such a channel or support is provided at each floor landing. On each channel is provided a vertical track 11, which is T-shaped, as is shown in Fig. 8.

An elongated carrier 12 is mounted to slide vertically on the track and a clamp housing 13 is secured to one side of the carrier at the lower end thereof. The housing has a vertical channel extending therethrough, one side being defined by a groove 14. A prime mover in the form of an endless cable 15 extends through the channel of the housing, so as to be clamped by a follower 16 having a vertical groove 17 for receiving said cable.

The cable passes around a lower pulley 18 at the bottom of the elevator shaft and a pulley 19 at the top of said shaft. The pulley 19 is driven by a reduction drive 20 (forming no part of the invention) which in turn is driven by a belt 21 from an electric motor 22. The belt 21 is driven by a pulley 23 connected with the motor by a friction clutch 24, such as is in common use, for permitting the pulley to slip when travel of the cable is interrupted.

At each floor landing suitable doors are located and I have shown a pair of sliding doors 25 of the usual construction. To the forward door a lever 26 has its forward end pivoted; while its rear end is pivoted to the outer end of a link 27 having its inner end pivoted to one side of the carrier 12. A supporting arm 28 has one end pivoted to the side of the channel 10 and the other end piv-

oted to the lever 26 inwardly of the link 27. Normally the carrier 12 and the housing 13 are locked in the elevated position shown in Fig. 1, whereby the doors are locked in their closed position, as will be hereinafter described. When the carrier is released, it will slide, due to its weight, down the track 11 to the position shown in Fig. 2, whereby the doors will be opened. As the carrier moves downwardly the link 27 will pull the rear end of the lever 26 downwardly and this lever will fulcrum on the arm 28, which will also be swung downwardly. When the carrier is elevated, as hereinafter described, the link 27 will exert an upward thrust on the lower end of the lever 26 and the latter being fulcrumed on the arm 28 and pivoted at its upper end to one of the doors, such action will start the doors to slide in their closing operation. The closing operation will be continued as the carrier moves upwardly. When the doors are fully closed the lever 26 is brought to nearly a horizontal position and the link 27 and arm 28 reach an acute angular relation, whereby the doors are securely held in their closed position.

When the motor 22 is not energized its armature and pulley 23 are free to turn in a reverse direction and consequently the cable 15 and its driving connections are free to be moved. It will be seen that if the carrier is clamped to the cable when said carrier is moved downwardly the cable will be moved by the carrier and, therefore, when the motor 22 is energized and placed in operation the cable will be caused to travel upwardly, thereby elevating the carrier.

For controlling the clamping, a bell crank lever 29 is fastened on the trunnion 30 of an eccentric 31 journaled in the housing 13, as is shown in Figs. 5, 6 and 7. The eccentric contacts with the follower 16 and when the lever 29 is swung in a clockwise direction (Fig. 5) the eccentric will be rotated so as to force the follower block into engagement with the cable 15 and thereby clamp the same. When the lever is swung in a counter-clockwise direction (Fig. 5), the eccentric will be rotated away from the block, whereby the cable will be freed.

A rectangular bolt 32 is mounted to slide horizontally in the housing 13 and projects from the rear end of said housing so as to engage in an aperture 33 (Figs. 2 and 8) in the channel 10 for locking the carrier in its elevated position. A stud 34 secured in the bolt extends through a slot 35 in the side of the housing and is journaled in a slot 36 in the lower end of the lever 29. When the lever is swung in a clockwise direction (Fig. 5), the bolt will be drawn into the housing and withdrawn from the aperture 33 at the time the housing is clamped to the cable. When the lever is swung to unclamp the cable, the

bolt will be slid from the housing into said aperture to lock the carrier in position.

For actuating the lever 29 two rollers 37 and 38 are journaled in spaced relation on a shaft 39 on the upper end of said lever. A bar 40 secured to the side of the channel overhangs the housing when the carrier is elevated, and is provided with a cam edge 41 in the path of the roller 37. When the carrier is elevated the roller 37 engages the cam 41, whereby the lever is swung to unclamp the cable and also to engage the bolt 32 in the aperture 33 to lock the carrier in position.

For operating the device a vertical shoe 42 is provided on the elevator car A. This shoe is pivotally supported by a link 43 and a lever 44, both pivoted in a keeper 45 secured to the elevator car. The lever 44 is pivoted intermediate its ends and is adjustably connected with a pitman 46 on the inner side of the keeper, said pitman having adjustable connection at its upper end with an arm 47 also pivoted in the keeper. The outer end of the arm is pivoted to the upper end of a rod 48.

Normally the shoe occupies the position shown in full lines in Figs. 1 and 9 and when in such position the shoe will pass the roller 38 without engaging the latter. When the rod 48 is pulled downward the arm 47 will be swung downward, which will cause the lever 44 to swing, through the agency of the pitman 46, to a horizontal position whereby the shoe 42 will be swung upwardly and outwardly, as is shown in full lines in Fig. 2 and in dotted lines in Fig. 9. For operating the rod 48 to swing the shoe a bell crank lever 49 is pivoted to the under side of the floor of the elevator car and said lever is connected by a link 50 with a bell crank lever 51 to which the stem of a foot treadle 52 is pivoted. The stem of the treadle extends through the floor of the car and said treadle is supported by a coil spring 53.

In operating the apparatus the parts are normally in the position shown in Fig. 1 so that the doors 25 at each floor landing are closed and the carrier 12 is locked in its elevated position by the bolt 32 which is engaged in the aperture 33. The motor 22 is idle and the shoe 42 is lowered out of the path of the roller 38 at each floor. With the parts thus arranged the elevator car may travel up and down the shaft and there will be no mechanical contacts with the door operating means and consequently no objectionable noise.

When the operator desires to stop the car and open the doors at a selected floor landing, he places his foot upon the treadle 52 and depresses the same, whereby the bell crank lever 51 is swung and through the agency of the link 50 swings the lever 49 from the position shown in Fig. 1 to the position shown in Fig. 2. This operation pulls the rod 48

downward, whereby the shoe 42 is projected into the path of the roller 38, as is shown in Fig. 2. As the car moves to the floor landing one of the rounded ends of the shoe will engage the roller 38 and displace the same so as to cause it to ride along the face of the shoe. When the roller is displaced, the lever 29 will be swung in a clockwise direction (Figs. 1 and 5) which will first actuate the eccentric 31 and cause the follower 16 to clamp the cable 15 and then withdraw the bolt 32 from the aperture 33. The carrier, thus being released, will slide down the track 11, thereby opening the doors 25 through the agency of the link 27 and the lever 26. The carrier and housing and attached parts are heavy enough to swing the lever 26 and cause the opening operation.

When the cable is clamped it will, of course, be moved downwardly with the carrier, the motor and driving mechanism being turned in a reverse direction. After the doors are opened the operator removes his foot from the treadle 52, whereby the shoe 42 is lowered to its inoperative position. When it is desired to close the doors the operator depresses a switch button or other device to close the motor circuit (not shown), whereby the electric motor 22 is energized. The motor imparts motion through the pulley 23 and clutch 24 to the belt 21, which revolves the pulley 19 in a clockwise direction (Fig. 1) through the agency of the reduction drive 20. This imparts motion to the cable 15 and the carrier 12, being clamped to said cable, is thus elevated.

As the carrier moves upwardly the lever 26 is swung through the instrumentality of the link 27, whereby the doors 25 are closed. When the carrier reaches its upper position the roller 37 engages the cam 41, whereby the lever 29 is swung in a counter-clockwise direction (Figs. 1 and 5). The swinging of the lever operates the eccentric 31 to release the cable and also projects the bolt 32 into the aperture 33. The friction clutch 24 permits the cable to slip in case the follower 16 is not promptly released. The operation is simple and positive.

The principle of the invention is exemplified in a door opening device normally locked against operation and arranged to automatically open the door when released, and also involving a normally idle prime mover to which the operating device is clamped when released, so that when said prime mover is energized the mechanism will be operated to close the door and also the mechanism will be unclamped from the prime mover and locked in position.

Various changes in the size and shape of the different parts, as well as modifications and alterations, may be made within the scope of the appended claims.

What I claim, is:

1. In an elevator door operating apparatus, door operating means, automatic door opening means connected with said door operating means and normally locked against operation when the door is closed, means carried by the elevator car for releasing the automatic opening means, a prime mover, means for connecting the opening means with the prime mover when the door is opened to cause said door to close upon the actuation of said prime mover, and means for releasing the opening means from the prime mover when the door is closed.

2. In an elevator door operating apparatus, door operating means, vertically movable opening means connected to the operating means, a lock connected to the opening means to lock the same in position when the door is closed, means for actuating the lock to release the opening means, and means to actuate the lock to prevent actuation of the door opening means.

3. In an elevator door operating apparatus, door operating means, vertically movable opening means connected to the operating means, a lock connected to the opening means to lock the same in position when the door is closed, means for actuating the lock to release the opening means to open the door, means for actuating the movable door opening means to close the door, and means to actuate the lock to prevent actuation of the door opening means.

4. In an elevator door operating apparatus, door operating means, vertically movable door opening means connected to the door operating means, means for locking the opening means in an elevated position, means carried by the elevator car for releasing the locking means to permit the opening means to move downwardly to open the door, means for elevating the door opening means to close the door, and means for actuating the locking means when the door means is elevated to its locking position.

5. In an elevator door operating apparatus, door operating elements, a carrier connected with said elements and mounted for vertical movement and arranged to slide downwardly under its own inertia to open the door, a prime mover, a clamp carried by the carrier, and means carried by the elevator car to actuate the clamp to engage the prime mover for closing the door.

6. In an elevator door operating apparatus, door operating elements, a carrier connected with said elements and mounted for vertical movement and arranged to slide downwardly under its own inertia to open the door, a prime mover, a clamp carried by the carrier, means carried by the elevator car to actuate the clamp to engage the prime mover, and means for actuating the clamp to release it from the prime mover.

7. In an elevator door operating apparatus, door operating elements, a carrier connected with said elements and movable vertically to operate said elements to open and close a door, a lock carried by the carrier for holding said carrier in an elevated position, and means carried by the elevator car for actuating the lock to release the carrier and permit the latter to move downwardly, and means for elevating the carrier.
8. In an elevator door operating apparatus, door operating elements, a carrier connected with said elements and movable vertically to operate said elements to open and close a door, a lock carried by the carrier for holding said carrier in an elevated position, and means carried by the elevator car for actuating the lock to release the carrier and permit the latter to move downwardly, means for elevating the carrier, and means to actuate the lock when the carrier is elevated to fasten said carrier in position.
9. In an elevator door operating apparatus, the combination with a movable door, of a vertically slidable carrier, operating means connecting the carrier with the door, a lock carried by the carrier for holding the latter elevated and the door closed, and means carried by the elevator car for actuating the lock to release the carrier to allow the latter to slide downward by gravity and actuate the connecting means to open the door.
10. In an elevator door operating apparatus, the combination with a movable door, of a vertically slidable carrier, operating means connecting the carrier with the door, a lock carried by the carrier for holding the latter elevated and the door closed, means carried by the elevator car for actuating the lock to release the carrier to allow the latter to slide downward by gravity and actuate the connecting means to open the door and means for elevating the carrier to close the door.
11. In an elevator door operating apparatus, the combination with a movable door, of a vertically slidable carrier, operating means connecting the carrier with the door, a lock carried by the carrier for holding the latter elevated and the door closed, means carried by the elevator car for actuating the lock to release the carrier to allow the latter to slide downward by gravity and actuate the connecting means to open the door, a vertically movable member, and a clamp attached to the carrier and set to clamp the said member when the carrier is released.
12. In an elevator door operating apparatus, door operating means, a vertically slid-
60 able carrier directly connected to said operating means, a lock carried by the carrier, a vertically movable member, a clamp carried by the carrier for engaging the said member, and an element carried by the carrier for actuat-

ing the lock and the clamp, and means carried by the elevator car for actuating the said element to release the lock and engage the clamp.

13. In an elevator door operating apparatus, door operating means, a vertically slide-
70 able carrier directly connected to said operating means, a lock carried by the carrier, a vertically movable member, a clamp carried by the carrier for engaging the said member, an element carried by the carrier for actuating the lock and the clamp, means carried by the elevator car for actuating the said element to release the lock and engage the clamp, and means in the path of said element to actuate it to release the clamp and engage the lock.

14. In an elevator door operating apparatus, the combination with a horizontally slide-
75 able elevator door, of door operating means connected with said door, automatic door opening means connected with said door operating means and normally locked against operation when said door is closed, a door closing element normally disconnected from the opening means, means for releasing the door opening means to open the door and for causing said means to connect with the closing element, and means for actuating said door closing element to close the door.

15. In an elevator door operating apparatus, the combination with a horizontally slide-
90 able elevator door, of elements for sliding said door horizontally connected thereto, a vertically slide-
100 able automatic door opening member to which said door sliding elements are connected, means directly engaged with said vertically slideable member for locking it against movement, whereby said door is closed, means carried by the car for releasing said door operating member to permit it to slide downward to actuate the door sliding elements to open said door, and means for engaging said member and elevating it to close said door.

In testimony whereof I affix my signature.
GUY L. ALLEN.
